[57] **CLAIM**

The ornamental design for a handheld lighted mirror device for inspecting the mouth or other parts of the human body, as shown and described.

DESCRIPTION

FIG. 1 is a front view of handheld lighted mirror device for inspecting the mouth or other parts of the human body embodying our new design;

FIG. 2 is a right side view thereof;

FIG. 3 is a rear view thereof;

FIG. 4 is a left side view thereof;

FIG. 5 is a top plan view thereof;

FIG. 6 is a bottom plan view thereof;

FIG. 7 is a perspective view thereof; and

FIG. 8 is a perspective view of the device in an operational mode.

The broken lines representing the human hand are shown for illustrative purposes only.
